ROBERT M. DE VIGNIER, OF BELLEFONTE, DELAWARE, ASSIGNEE, BY MESNE ASSIGNMENTS, TO NATIONAL VULCANIZED FIBRE CO., OF WILMINGTON, DELAWARE, A CORPORATION OF DELAWARE.

MANDREL EXTRACTOR.

Application filed February 15, 1922. Serial No. 536,679.

To all whom it may concern:

Be it known that I, ROBERT M. DE VIGNIER, a citizen of the United States, and a resident of Bellefonte, county of New Castle, 5 State of Delaware, have invented a certain new and useful Improvement in Mandrel Extractors, of which the following is a specification.

Some of the objects of the present invention are to provide an improved mechanism 10 for extracting mandrels from formed fibre tubes or tubes of other material; to provide means for removing mandrels from tubes without damaging the finished tubes; 15 to provide means for automatically attaching a removing device to a mandrel, withdrawing such mandrel from a tube, and automatically releasing the extracted mandrel; to provide continuously acting means 20 for successively extracting mandrels from finished fibre tubes; to provide means for varying the stroke and operation of a mandrel extracting machine for mandrels of different length; and to provide other improvements 25 as will hereinafter appear.

In the accompanying drawings, Fig. 1 represents a side elevation of a mandrel extracting machine embodying one form of the present invention; Fig. 2 represents an 30 end elevation of the same; Fig. 3 represents a plan of a head block showing one form of jaw actuating mechanism; Fig. 4 represents a side elevation of the parts shown in Fig. 3; Fig. 5 represents a section on line 5-5 of Fig. 4; and Fig. 6 represents a section on line 6-6 of Fig. 5.

Referring to the drawings, one form of the present invention consists of a frame 10 preferably arranged to support means for 40 alternately extracting mandrels from opposite ends of the machine, and to accomplish such result end standards 11 are provided, each pair of such standards supporting a head 12 having a through opening 13 therein, the diameter of which is arranged to freely pass the largest size mandrel which it is contemplated will be employed.

In the present machine a mandrel 14 carrying a formed tube 15 of fibre or other 50 material is inserted through the opening 13 with the end of the tube 15 abutting a fixed part so that by pulling the mandrel 14 axially through the opening 13 while the

tube 15 is held against movement the mandrel 14 is withdrawn therefrom. Preferably 55 the outer face of the head 12 about the opening 13 is counterbored to receive a tubular die 16 which is fixed in place by a set screw 17 or other fastening means. By using dies with different size openings the machine 60 is adapted for use with different sized mandrels in accordance with the size of tube being formed.

In view of the fact that the mandrel engaging devices for the two ends of the 65 machine are of duplicate construction, and operate in like manner, the present description may be simplified by reference to the parts of one of these devices and by applying corresponding reference numerals 70 to like parts in the other.

For the purpose of gripping the flanged end of the mandrel 14 to cause its withdrawal from the tube 15, a head block 20 is provided carrying a pair of oppositely 75 arranged jaws 21 which are pivoted respectively upon trunnion pins 22 laterally projecting to either side of two leader nuts 23. One of the nuts 23 has screw threaded engagement with a left hand thread 24 upon 80 a feed screw 25, while the other nut 23 has screw threaded engagement with a right hand thread 26 also upon the screw 25. The ends of the screw 25 are arranged to be accessible from the outside of the block 20 85 so that the screw 25 may be turned by any suitable means to vary the distance between the nuts 23 and thus adjust the jaws 21 for varying sizes of mandrels. Each of the jaws 21 is provided with a lip 27 which is 90 arranged to seat back of the flanged portion of the mandrel end in closed position of the jaws to draw the mandrel axially as desired.

In order to automatically open and close 95 the jaws 21, the head block 20 is provided with a recess 30 arranged to receive and guide a slide member 31 which in the present construction carries at one end a T-head 32, the ends of which seat respectively 100 in slots 33 of the respective jaws 21, though with sufficient clearance to permit free relative movement of the parts. At the opposite end of the member 31 is a similar head 34, the outer end surface of 105 which is engaged by coiled springs 35 which

seat against the block 20 and normally tend to maintain the head 34 in contact with two eccentrics 36 located at opposite sides of the body of the member 31. The eccentrics 36 are respectively rigid with two vertically journalled pins 37 which project exterior of the block 20 to receive respectively two levers 38, which lie in the same plane. These levers 38 are rigid with the respective pins 37 and in closed position of the jaws 21 their outer ends abut to limit their movement in one direction, while in the opposite direction their movement is limited by the engagement of the eccentrics 36 with the 15 walls of the recess 30.

For actuating the levers 38 the outer or free end of each carries a projecting lug shown here in the form of a roller 40, the arrangement being such that in closed position of the jaws 21 the rollers 40 are relatively close together to be engaged by an opening cam 41 and separated, while in open position of the jaws 21 the rollers 40 are spaced apart to be engaged by a closing 25 cam 42. The opening cam 41 is arranged to be secured to a fixed part of the machine in the path of movement of the rollers 40 and in a predetermined position for correct timing of the opening of the jaws 21, and is 30 provided with a tapered cam nose 43. As the head block 20 moves in one direction, as will be explained, the rollers 40 meet the cam nose 43 and are swung on diverging arcs to a position which determines the open 35 position of the jaws 21. The closing cam 42 is located at the opposite side of the block 20 in the path of the rollers 40 and is secured to a fixed part of the machine in a predetermined position for correct timing 40 of the closing of the jaws 21. The cam 42 comprises two forwardly projecting fingers 44 having inclined faces 45 respectively 45 which converge toward a transversely disposed plane cam face 46, the construction being such that when the block 20 moves past the cam 42 the cam faces 45 respectively engage the rollers 40 and initially swing them toward each other whereupon the cam face 46 engages both rollers 40 and moves them 50 to a position determining the closed position of the jaws 21.

As a means for movably mounting and reciprocating the block 20, it is provided with supporting wheels 47 arranged in pairs at 55 opposite sides of the block 20, the pairs of wheels respectively travelling upon suitable rail members 48 rigidly carried by the standards 11. Centrally disposed with respect to the frame 10 there is a prime mover 60 in the form of a cylinder 50 having a piston 51 therein from which axially disposed piston rods 52 and 53 extend in opposite directions through the ends of the cylinder to connect respectively to the head blocks 20. 65 The prime mover 50 is of any well known

type arranged to operate by pressure fluid alternately admitted to opposite ends of the cylinder by any suitable type of valve structure (here deemed unnecessary to illustrate), the reciprocable valve rod 54 thereof being 70 shown extending longitudinally of the frame 10 in opposite directions from the cylinder 50 but parallel to the path of movement of the blocks 20 as controlled by the piston rods 52 and 53. 75

For actuating the valve rod 54 two tappets or trip fingers 55 are fixed to the rod 54 by set screws 56 or other rigid fastening means which will permit adjustment of the tappets 55 from one longitudinal position to another to vary the timing of the valve action, so that the piston stroke may be changed according to requirements, such for example as different length mandrels. Normally each tappet 55 is located on the valve 80 rod 54 on the opposite side of its head block 20 from the cylinder 50, and in the path of movement of a lug 57 upon that block 20. The contact relation between the respective tappets 55 and the lugs 57 is such that the 85 valve rod 54 is shifted to reverse the prime mover substantially at the time the jaws 21 have operatively interlocked with the mandrel to be removed. Thus the valve rod 54 is alternately shifted as first one head block 90 20 and then the other assumes its mandrel withdrawing position.

In order to receive and deliver the mandrels from the machine when they have been withdrawn from the tubes and released by 100 the jaws 21, each end of the present machine is provided with a platform 60 fixed to the frame 10 in an inclined position to cause the released mandrels to roll laterally by gravity and be delivered at the side of the machine where they can be removed for use 105 again.

In the operation of the machine motive fluid is supplied to the cylinder 50 and the head blocks 20 are mutually reciprocated in 110 a continuous manner so that when one block 20 is withdrawing a mandrel from a tube, the operator is placing another mandrel supported tube in position at the other end of the machine. This is accomplished by inserting the projecting flanged end of the mandrel through the die 16 with the tube end abutting the face of the die 16, and will be here assumed as taking place at the right hand end of the machine as shown in Fig. 1, 120 while a mandrel is being extracted at the other end of the machine.

When the approaching head block 20 reaches the predetermined position relative to the mandrel end, the closing cam 42 is 125 met by the rollers 40, which then ride toward each other upon the finger cam faces 45 and pass into engagement with the flat cam face 46. This action causes the levers 38 to turn through the necessary angle to swing the 130

eccentrics 36 and thus shift the member 31, to rigidly clamp back of the flange on the mandrel end. As this takes place the lug 57 on the head 20 meets the tappet 55 and motion is then transmitted to the valve rod 54, which moves to the right as shown in Fig. 1 to reverse the slide valve of the prime mover. Substantially at the same time that the head block 20 at the right is closed the other head block 20 reaches the position where its opening cam 41 rides between the rollers 40 to cause the levers 38 to move the eccentrics 36 so that the member 34 slides under the action of the springs 35 in a direction to cause the jaws 21 to open. This releases the extracted mandrel which drops to the inclined table 60 and is delivered to the side of the machine. The prime mover now functions to draw the held mandrel from its tube while another tube and mandrel are placed in position at the left end of the machine to repeat the foregoing operation. In this way alternate extracting operations are carried out so that there may be substantially continuous extracting operations whereby mandrels may be quickly removed from finished tubes and returned without delay for use again in tube forming operations.

The machine here shown by way of illustration is provided with two extracting heads so that a more continuous extracting action can be carried out towards increased production of finished tubes, but it is to be understood that the invention comprehends a structure including one or more heads and is not to be limited by the illustrated disclosure.

Having thus described my invention, I claim:

1. In a mandrel extracting machine, the combination of a clamping device arranged to engage a mandrel having a tube thereon, means for causing said device to be clamped to said mandrel, power actuated means for moving said clamping device in a direction to extract said mandrel from said tube, and means for preventing said tube moving in the same direction during said extracting operation.

2. In a mandrel extracting machine, the combination of a clamping device arranged to engage a mandrel having a tube thereon, means for causing said device to be clamped to said mandrel, power actuated means for moving said clamping device in a direction to extract said mandrel from said tube, means for preventing said tube moving in the same direction during said extracting operation, and means for automatically releasing said mandrel at a predetermined time.

3. In a mandrel extracting machine, the

combination of a clamping device arranged to engage a mandrel having a tube thereon, means for causing said device to be clamped to said mandrel, power actuated means for moving said clamping device in a direction to extract said mandrel from said tube, means for preventing said tube moving in the same direction during said extracting operation, means for automatically releasing said mandrel at a predetermined time, and a delivery device for the extracted mandrel.

4. In a mandrel extracting machine, the combination of a movably mounted head block, a clamping device carried thereby and arranged to engage a mandrel having a tube thereon, power means for reciprocating said head block, means operating at a predetermined time on the non-working stroke of said power means for causing said clamping device to close to grip said mandrel, means operating at a predetermined time on the working stroke of said power means for causing said clamping device to open to release said mandrel, and means for preventing said tube moving with said mandrel.

5. In a mandrel extracting machine, the combination of a movably mounted head block, a clamping device carried thereby and arranged to engage a mandrel having a tube thereon, power means for reciprocating said head block, means operating at a predetermined time on the non-working stroke of said power means for causing said clamping device to close to grip said mandrel, means operating at a predetermined time on the working stroke of said power means for causing said clamping device to open to release said mandrel, means for preventing said tube moving with said mandrel, and means controlled by said block for reversing said power means.

6. In a mandrel extracting machine, the combination of a movably mounted head block, clamping jaws pivoted to said block and arranged to engage a mandrel having a tube thereon, means for actuating said jaws to open or close to engage or release said mandrel, power means for reciprocating said head block, means located adjacent the path of movement of said block for causing said actuating means to function at predetermined times, and means for preventing said tube moving with said mandrel.

7. In a mandrel extracting machine, the combination of a movably mounted head block, clamping jaws pivoted to said block and arranged to engage a mandrel having a tube thereon, means including members projecting from said block for actuating said jaws to open or close to engage or release said mandrel, power means for reciprocating said head block, means located in the path of movement of said members for causing said actuating means to function at pre-

determined times, and means for preventing said tube moving with said mandrel.

8. In a mandrel extracting machine, the combination of a movably mounted head block, clamping jaws pivoted to said block and arranged to engage a mandrel having a tube thereon, means including a slide member for actuating said jaws to open or close to engage or release said mandrel, power means for reciprocating said head block, means located adjacent the path of movement of said block for causing said actuating means to function at predetermined times, and means for preventing said tube moving with said mandrel.

9. In a mandrel extracting machine, the combination of a movably mounted head block, clamping jaws pivoted to said block and arranged to engage a mandrel having a tube thereon, means including a spring pressed slide member for actuating said jaws to open or close to engage or release said mandrel, power means for reciprocating said head block, means located adjacent the path of movement of said block for causing said actuating means to function at predetermined times; and means for preventing said tube moving with said mandrel.

10. In a mandrel extracting machine, the combination of a movably mounted head block, clamping jaws pivoted to said block and arranged to engage a mandrel having a tube thereon, means including a spring pressed slide member and an eccentric mechanism for actuating said jaws to open or close to engage or release said mandrel, power means for reciprocating said head block, means located adjacent the path of movement of said block for causing said actuating means to function at predetermined times, and means for preventing said tube moving with said mandrel.

11. In a mandrel extracting machine, the combination of a movably mounted head block, clamping jaws pivoted to said block and arranged to engage a mandrel having a tube thereon, means including trip rollers projecting from said block for actuating said jaws to open or close to engage or release said mandrel, power means for reciprocating said head block, means located in the path of movement of said trip rollers

for causing said actuating means to function at predetermined times, and means for preventing said tube moving with said mandrel.

12. In a mandrel extracting machine, the combination of a plurality of clamping devices arranged respectively to engage mandrels having tubes respectively fast thereon, means for alternately causing said devices to be clamped respectively to said mandrels, power actuated means for simultaneously reciprocating said clamping devices to alternately extract said mandrels from said tubes, and means for preventing said tubes moving in the same direction as the respective mandrels.

13. In a mandrel extracting machine, the combination of two oppositely arranged fixed heads having openings respectively for the passage of mandrels, a pair of head blocks mounted to reciprocate between said heads, clamping jaws carried by each block and arranged to engage oppositely located mandrels, means for actuating the respective jaws to open or close to engage or release a mandrel, power means for reciprocating said block, means located adjacent the path of movement of said heads for causing said actuating means to function at predetermined times, and means for preventing a tube carried by any mandrel from moving with said mandrel.

14. In a mandrel extracting machine, the combination of two oppositely arranged fixed heads having openings respectively for the passage of mandrels, a pair of head blocks mounted to reciprocate between said heads, clamping jaws carried by each block and arranged to engage oppositely located mandrels, means for actuating the respective jaws to open or close to engage or release a mandrel, power means for reciprocating said block, means located adjacent the path of movement of said heads for causing said actuating means to function to open one set of jaws and close the other set of jaws, and means for preventing a tube carried by any mandrel from moving with said mandrel.

Signed at Wilmington, in the county of New Castle, and State of Delaware, this 10th day of February, 1922.

ROBERT M. DE VIGNIER.
